SNAP LOCK

Everett Worthington, deceased, late of Scarsdale, N. Y., by Lucile Worthington, administratrix, Berkeley, Calif., assignor to American Can Company, New York, N. Y., a corporation of New Jersey

Application October 12, 1939, Serial No. 299,220

2 Claims. (Cl. 292—209)

The present invention relates to a snap-catch for luggage or the like and has particular reference to and has as an object the provision of a snap-catch which is simple in construction and of an improved design which will hold tightly when closed and which may be readily opened.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a snap-catch embodying the instant invention, the catch being shown in open position and secured in place to a piece of luggage only a portion of which is illustrated;

Fig. 2 is a view similar to Fig. 1 and showing the catch in closed position; and

Fig. 3 is a sectional view taken substantially along a plane indicated by the lines 3—3 in Fig. 2.

As a preferred embodiment of the invention, the drawing discloses a sheet metal snap-catch which includes a latch body member 11, a keeper or cover member 12 and a movable catch or latch element 13. The body member 11 is preferably formed with a hollow flat and rectangular shaped base plate 15 having peripheral flanges 16. The base plate is rigidly secured by lugs 17 to the body portion of a piece of luggage 18 such as a lunch kit, box or the like. These lugs 17 are formed on two opposing flanges 16 of the base plate and extend through slots 19 formed in the luggage. The lugs are bent outwardly against the inside surface of the luggage and thus hold the body member 11 in place.

The body member 11 carries the catch element 13. For this purpose the base plate 15 of the body member is formed with a hollow boss 21 having straight and flat side wall sections 22 and a flat front wall section 23. At its upper end the boss is open and at its lower end the front wall section curves inwardly towards the base plate and merges with it.

The boss 21 encloses a flat leaf spring 25. One end of the spring is straight and is disposed in a stepped recess constituting a shoulder 26 formed in the boss where the front wall merges into the base plate 15. The other end of the spring is partially curled inwardly as at 27 and this curled end is adapted to slide on the inner surface of the boss. A flange 28 on the boss front wall section 23 at its upper edge prevents displacement of the spring.

The catch element 13 is formed with an elongated outwardly bent and substantially half-round catch wall section 31 having on one side thereof two depending bent leg sections 32. These leg sections straddle and extend down adjacent the side wall sections 22 of the body member boss 21. The lower extremities of the leg sections are provided with inwardly projecting flat lugs 34 which extend into holes 35 formed in the boss side wall sections 22 and these lug sections engage against the leaf spring 25. Above the catch wall section 31 the element is formed with a broad outwardly curved finger hold portion 37.

15 Hence the catch element 13 may be hinged on its lugs 34 relative to the body member 11 and when so hinged the lugs press against the spring which thereby exerts a pressure on them. Thus when the flat sides of the lugs 34 are against the spring 25 the latter holds the catch element 13 in an upright position as shown in Figs. 2 and 3. This is the catch locking position. When the catch element is hinged into a laterally extended or unlocked position as shown in Fig. 1, 20 the edges of the flat lugs 34 engage the spring 25 and the latter thus retains the catch element in this position.

25 When the catch element 13 is in its upright or locking position it interlocks with the cover member 12. This cover member includes a hollow base plate 41 which is surrounded on three sides with flanges 42. The two end flanges have holding lugs 43 which extend through slots 44 in a cover 45 of the luggage and are bent outwardly against the inner surface of the cover in order to hold the cover member 12 in place.

30 The cover member 12 is supported against torsional stresses by a U-shaped overhanging lug 47 which is formed on the top flange 42 and which extends through a slot 48 in the luggage cover 45. The terminal edge of this U-shaped lug engages against the inner surface of the luggage cover beyond the area covered by the base plate 41 and thereby supports the base plate 42 against being sprung away from the luggage cover when the catch element 13 engages the cover member 12.

35 Along the lower edge of the base plate 41 the cover member 12 is formed with an elongated and outwardly projecting half-round catch wall section 52. It is this wall section that cooperates with and interlocks with the half-round catch wall section 31 of the catch element 13 when the latter is in its upright or locking position hereinbefore mentioned. In this position the inter-

locked half-round wall sections mesh and engage with one another, the catch element wall section overlapping and surrounding the cover member wall section thereby locking the cover member 12 with the body member 11 in a grip which is sufficiently strong to permit carrying the luggage from a handle or the like secured to the luggage cover.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

What is claimed is:

1. In a snap-catch for luggage or the like, including a sheet metal keeper member terminating in a depending substantially uniformly outwardly and inwardly curved projecting latch engaging portion, the combination of a sheet metal latch body member adapted to be secured to a piece of luggage in substantially the plane of the keeper, and a catch element hingedly connected to said latch body member and adapted to be hinged into locking position with said keeper member, said catch element including an elongated outwardly and inwardly substantially uniformly curved projecting half-round lock wall section which interlocks with and closely conforms to the curvature of the inwardly and outwardly curved terminal portion of said keeper when the catch element is in locking 35

position to thereby lock together said latch body member and said keeper.

2. In a snap-catch for luggage or the like including a sheet metal keeper member having an overhanging supporting lug extending inside the luggage for holding the keeper against displacement and terminating in a depending substantially uniformly outwardly and inwardly curved projecting latch engaging portion, the combination of a sheet metal latch body member adapted to be secured to a piece of luggage in substantially the plane of the keeper and having an overhanging supporting lug extending inside the luggage for holding said latch body member against displacement, a catch element hingedly connected to said latch body member and adapted to be hinged into locking position with said keeper member, said catch element including an elongated outwardly and inwardly substantially uniformly curved projecting half-round lock wall section which overlaps and interlocks with and closely conforms to the curvature of the inwardly and outwardly curved terminal portion of said keeper when the catch element is in locking position to lock together said latch body member and said keeper member, and a spring element housed in said latch body member and exerting a pressure against said catch element for removably holding the same in both locked and released positions.

LUCILE WORTHINGTON,
Administratrix of the Estate of Everett Worth-
ington, Deceased.
